UNITED STATES PATENT OFFICE.

IDA MARIE MAXIMILIANE ERNESTINE HÜBNER, OF DRESDEN, GERMANY.

INTERCONVERTIBLE COVERLET AND WRAPPER.

1,102,408.

Specification of Letters Patent. Patented July 7, 1914.

Application filed February 5, 1913. Serial No. 746,350.

To all whom it may concern:

Be it known that I, IDA MARIE MAXIMILIANE ERNESTINE HÜBNER, a citizen of the German Empire, and residing at 13 Fürstenstrasse, Dresden-A., Kingdom of Saxony, Germany, have invented certain new and useful Improvements in Interconvertible Coverlets and Wrappers, whereof the following is a specification.

10 The object of the present invention is to provide a coverlet for a couch, cot or bed, chiefly for hospitals, sanatoriums and the like, which coverlet will not only completely cover the patient, when recumbent, and at 15 the same time also allow of his free movements, particularly of his arms, but will besides allow of being used as a garment by the patient when he rises.

15 The advantage obtained by the coverlet according to the present invention consists in that the patient is not only covered in a hygienically satisfactory manner, while he is lying in bed, but that the changing from a recumbent to a standing position may be 20 effected without danger of his cooling down or the necessity of his having to change his garments.

25 The object of the present invention is obtained by providing a coverlet having an opening for the neck of the patient with slits through which he may pass his hands, and with covering means such as sleeves or lapels over these slits. When the coverlet has a counterpane, the sleeves are formed by 30 tubular attachments on the inner (under) side of the counterpane, and these tubular attachments are then drawn through the slits in the coverlet and slits in the upper side of the counterpane. The arrangement 35 may, however, also be such, that both the coverlet and also the counterpane are provided with sleeves.

40 Figure 1 represents a longitudinal section of this invention in its preferred form having sleeves which adapt it for use as a 45 wrapper and provided with a sleeved covering which serves as a counterpane when the device is used as a coverlet. Fig. 2 represents a similar section in which the sleeves 50 are omitted from the body of the coverlet or garment. Fig. 2^a shows an enlarged view of the sleeved connection of the counterpane shown in Fig. 2. Fig. 3 represents a longitudinal section of the garment coverlet, the 55 covering shown in Fig. 1 and Fig. 2 being omitted and the neck being provided with

a bib and the pocket with a detachable lining. Fig. 4 represents a plan or front elevation of the device in the form of a coverlet. Fig. 4^a represents a plan of a fragment 60 of the body *a* showing a scye slit therein covered by a lapel. Fig. 4^b represents a transverse section thereof. Fig. 5 represents a longitudinal section of one form of the garment coverlet. Fig. 6 represents the 65 interconvertible garment coverlet for use as a wrapper in sitting position. Fig. 7 represents the same for use in standing position.

70 The same reference characters indicate corresponding parts in the different figures.

The body *a* of this garment coverlet is made of camelhair, wool or other suitable material and is preferably bound with a braid *b*. This body is provided at one end, 75 preferably about midway of its width with a longitudinal slot *d* extending downward or inward a substantial distance from the upper edge of the body and provided at its inner end with an enlargement *c*. This slot 80 divides the upper end of the body and forms on opposite sides thereof two substantial back wings *e*, which when the article is used as a wrapper or garment, extend over the shoulders and across and down the back 85 forming a lung protector. The enlargement at the inner end of the slot *d* constitutes in such use a neck opening disposed a substantial distance below the top of the body.

90 Means are provided for fastening the back wings or lung protectors in wrapping position over the shoulders and down the back. The means herein shown are two snap buttons parts *g* of which are located at the outer corners of said shoulder wings and 95 the counterparts *g'* adjacent to the neck opening *c*. Means are also provided for folding upward and suspending around the waist the lower end of the body *a* when it is used as a garment for the patient in 100 standing position. The means shown for this purpose comprise two holes *o* at the lower corners of the body *a*, a loop *o'* on the inner face thereof and a waist cord or belt *o'* threaded through said holes and the loop 105 and adapted to encircle the waist as indicated in Fig. 7. The body *a* is also provided below the shoulder wings *e* with two slots *f* which constitute scyes for the passage of the arms. Means are provided for 110 covering these slits, the means shown comprising sleeves *g* as shown in Figs. 4 and 5

or lapels g' as shown in Figs. 4^a and 4^b. The sleeves are preferably provided at their front ends with means for preventing the entrance of cold air at the wrist, such for instance as a gathering string h . On the coverlet body a are also arranged pockets i , which may be provided with an exchangeable lining k' . This lining is buttoned to buttons l sewn to the coverlet or the pocket, and may be exchanged at any time, and will prevent the coverlet proper being soiled by handkerchiefs, sputum cups or the like placed into the pockets. For still further increasing the safety the lining may be made of some impermeable material.

A coverlet body as hereinbefore described, which will entirely cover the patient, while he is in a recumbent position, may serve as a garment without any further preparation, when the patient rises, all that is necessary is to pull a cord o' around the waist.

Figs. 4^a and 4^b illustrate the arrangement of a lapel g^1 which is attached to the slit f in the coverlet, so that this slit is entirely covered by the said lapel when the hands or arms are not passed through it, and thereby closed against the entrance of cold air and the like. The lapel may also be provided with a buttonhole buttoning over a button on the coverlet, whereby it will be held in such closing position.

In Fig. 2 the body a is provided with a cover n , whereof the inner face serves as a lining when said body is used as a wrapper and the outer or either face serves as a counterpane when the body is used as a coverlet. To the inner layer of the cover n is sewn a sleeve g . This sleeve is drawn from the position indicated by dotted lines through the slit f and through a corresponding slit in the outside of the cover n . For preventing the sleeve from being drawn back, when the arm is withdrawn, the sleeve is preferably secured to the edge of the slit of the outside of the counterpane. This may, for instance, be done by means of a cord laced in a zig-zag line as shown in Fig. 2 through the scallops of the counterpane and the sleeve respectively. The sleeve will thus form a protection for the edge of the slit f in the coverlet, and these edges can therefore not be soiled and infected by germs of the disease of the patient, waste products, sputum and the like, when he passes his hand and arm through the slit.

In Fig. 1 the coverlet body a and the cover both have sleeves. Here the coverlet a has a sleeve g , the cover n has a sleeve g^1 attached to its underside, which sleeve is drawn through the slit f in the coverlet a and is folded over the edge of the sleeve g . To the front side of the cover n is attached a sleeve g^2 , the front end of which is secured by suitable means, for instance knotting, lacing and the like, to the folded over edge

of the sleeve g^1 . Also here the edge of the slit f is protected against its being soiled, and the sleeve g of the coverlet is completely inclosed.

In Fig. 3 the counterpane is omitted and the coverlet body a is provided with a sort of bib m at the neck. This bib is made of an impermeable material and is buttoned to the chest section of the coverlet. Its edge is folded over the edge of the neck hole c , and buttoned on the inside to the coverlet. This bib will serve to protect the coverlet from being soiled by contact with the patient and prevent its being infected by his sputum.

I claim:

1. An interconvertible coverlet and wrapper comprising a substantially rectangular body adapted to cover a couch, cot or bed and provided with slits in its upper part adapted to constitute scyes and with an elongated slot extending a substantial distance inward or downward from the upper edge of said body and having an enlargement at its lower or inner end adapted to form a neck opening disposed a substantial distance below said upper edge, said enlarged elongated slot forming wings on its opposite sides adapted in the use of the article as a wrapper to constitute back flaps extending downward over the back.

2. An interconvertible coverlet and wrapper comprising a substantially rectangular body adapted to cover a couch, cot or bed and provided with slits in its upper part adapted to constitute scyes and with an elongated enlarged slot at its upper end adapted to form back covering wings and a neck opening, and means for supporting the lower end of said body at the front thereof at the waistline and forming two front layers below the waist when the device is used as a wrapper, leaving free the feet.

3. An interconvertible coverlet for a couch, cot or bed and wrapper comprising a substantially rectangular body adapted to cover a couch, cot or bed and provided with slits in its upper part adapted to constitute scyes and with an elongated enlarged slot at its upper end adapted to form back covering wings and a neck opening, and a cover corresponding in shape to said rectangular body and provided with scye slits and a slot corresponding with the slits and slot of said body, said cover being adapted to form a lining when the article is used as a garment and a counterpane when the article is used as a coverlet.

4. An interconvertible coverlet and wrapper comprising a substantially rectangular body adapted to cover a couch, cot or bed and provided with slits in its upper part adapted to constitute scyes, with sleeves surrounding said scyes and with an elongated and enlarged slot extending downward from

its upper end and adapted to form back covering wings and a neck opening, and a cover corresponding in shape to said rectangular body and provided with scye slits and a slot corresponding with the slits and slot of said body and with elongated sleeves at its scye slits, extending through the sleeves of said body and adapted to be turned back thereover, said cover being adapted to form 10 a lining when the article is used as a gar-

ment and a counterpane when the article is used as a coverlet.

In testimony whereof I have hereunto set my signature in the presence of two witnesses.

IDA MARIE MAXIMILIANE
ERNESTINE HÜBNER.
